UNITED STATES PATENT OFFICE

OTTO GREGAREK, OF PHILADELPHIA, PENNSYLVANIA

COMBINED INSOLE AND ARCH SUPPORT

Application filed April 21, 1930. Serial No. 445,848.

My invention relates to new and useful improvements in a combined insole and arch support, and has for one of its objects to construct a device of this character in such a manner that the arch support is carried by the insole either as an integral part thereof or as a separate element secured to the insole by stitches, an adhesive or other suitable means.

Another object of the invention is to so fashion the device that it may be produced entirely of felt and of such design or configuration that it will develop the proper medial tread, namely, a tread from the center of the heel on a substantially straight line forward through the great toe, thus bringing the bones of the foot in proper alignment and giving effective support to the arch.

A further object of the invention is to construct a device of the kind described in which the arch support element has its edges skived inwardly and upwardly toward the insole element so that when in use, portions of the insole will be depressed or deflected in accordance with the inclination of the skive and following the outline of the arch support element.

A still further object of the invention is to produce an article of manufacture in the form of a combined insole and arch support so fashioned that the arch supporting element depends from the insole element with spaces between the edges of the arch supporting element and the under face of the insole element produced by forming inclined or skived portions contiguous the under face of the insole element around or along all of the edges of the arch supporting element.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:—

Fig. 1 is an inverted plan view of the com-

bined insole and arch support constructed in accordance with my invention and with the outlines of the bones of a foot illustrated in connection therewith in dotted lines, the device herein shown being the one for use with the left foot.

Fig. 2 is a section on the line 2—2 of Fig. 1 illustrating the device in the position while in use.

Fig. 3 is a section on the line 3—3 of Fig. 1.

Fig. 4 is a view similar to Fig. 3 showing the position which the several parts assume when the device is actually under the pressure of a person's weight.

Fig. 5 is a top plan view of the arch support element as it would look separated from the insole element if severed from the latter in approximately the line 5—5 of Fig. 2.

In carrying out my invention as herein embodied, 9 represents a combined insole and arch support produced from suitable soft and compressible material, preferably felt, and including an insole 10 of proper shape to fit snugly within a shoe and an arch support 11 of unique configuration and said arch support is carried by the insole and depends from the under face of the latter.

In actual practice, the arch support can be an actual integral part of the insole by fusing the two elements from a section of material of sufficient thickness to include the thickness of both elements in the finished article or they may be manufactured as separate elements and afterwards fastened or secured together so as to become to all intents and purposes, integral with each other. This can be done by gluing or cementing, by stitching or otherwise fastening the arch support to the under side of the insole or a blank may be built up to provide a central portion of one thickness surrounded by a flange of another thickness and said blank afterwards fashioned according to the structural details to be presently described.

The body of the arch support 11 extends lengthwise of the insole 10 in the region of the longitudinal center of the insole and in the locality of the position assumed by the arch of a wearer's foot when the device is in use and from the rear end and on that side of the

insole upon which the small toe of the foot rests, the arch support is provided with an extension 12 which projects to the edge of the insole and the rear portion of the support including this extension is skived at a greatly increasing angle from the outer edge of the extension to the opposite edge of the support as indicated at 13 and said skiving produces an inclined surface on the arch support which surface projects inwardly and upwardly as clearly shown in Fig. 2.

I wish to state at this time that all of the skiving referred to herein will be similar to that just mentioned so that the inclined surfaces are all between the under face of the insole and the body of the support or generally it might be said that the inclined surfaces becoming the upper faces of the support when the device is considered as a finished article. On the internal side near the forward end of the support is formed an extension 14 which projects beneath the forward end of the first metatarsal bone and on the external side is formed an extension 15 which projects under the forward end of the fifth metatarsal bone and the forward end of the support is slightly curved convexly so as to underlie the anterior arch.

Both the internal and external sides as well as the forward end of the support are skived as indicated at 16, 17 and 18 respectively in the manner above described or inwardly and upwardly from the edges of the support. The rear portion of the support including the extension 12 is intended to support the posterior arch comprising the internal cuneiform, middle cuneiform, external cuneiform and cuboid bones and because of the skiving, the insole element in the region of the rear edge of the support element will follow the downwardly and outwardly inclined portion of said support element so as to provide a blending surface from an elevated level to a lower level at the heel, thereby tending to hold the foot in proper position within the shoe.

The forward portion of the support being of a shape to properly support the anterior arch, the skiving 18 along the front edge of the support will cause the insole in the region of said forward edge of the support to be gradually inclined downwardly thereby giving the proper curvature to the underside of the foot from the anterior arch toward the front end of the foot.

The point blending between the skiving 18 with the skiving 17 is intended to extend between the joint of the big toe and the joint of the second toe so as to properly position these joints and prevent crowding which it is essential to maintain the proper tread.

A support made as above described will develop the proper medial tread from the center of the heel on a straight line forward including the great toe; thus bringing the bones of the foot in proper alignment and in

proper elevations relative to each other to advantageously support the posterior, longitudinal and anterior arches including the metatarsal arch.

The device being made entirely of suitable compressible or yielding material, preferably felt, provides a soft resilient or yielding tread to the foot throughout and yet gives sufficient support to the arch to keep the bones in proper relative positions. The device also being of compressible or yielding material avoids any hard pressure upon the under side of the front and tends to prevent or remedy foot ailments. The device also being absorbent will take up perspiration so as to prevent or lessen the likelihood of disagreeable odors since such device may be readily removed for cleansing and airing. It also corrects the position of the bones of the foot and prevents friction between the foot and shoe or other actions which tend to form callouses so that where devices of this kind are used, the wearer's foot is generally free to such growths.

Of course I do not wish to be limited to the exact details of construction as herein shown, as these may be varied within the limits of the appended claims without departing from the spirit of my invention.

Having thus fully described my invention, what I claim as new and useful is:—

1. A device of the kind described comprising an integral structure consisting of an insole, an arch support on the under side of the insole, said support having an extension projecting toward the external side of the insole at the rear end of the support, another extension near the forward end projecting on the interior side of the support and the forward end of said support being curved convexly and all the edges except the outer end of the first mentioned extension being skived to provide inclined surfaces projecting inwardly and upwardly, said inclined surfaces being contiguous the under surface of the insole so that when in use said insole will be inclined toward its edges.

2. The structure set forth in claim 1 in combination with a third extension projecting from the external side of the support near the forward end.

In testimony whereof, I have hereunto affixed my signature.

OTTO GREGAREK.
